UNITED STATES PATENT OFFICE.

ERNEST OSCAR THALINGER, OF ST. LOUIS, MISSOURI.

GAME.

1,299,520.

Specification of Letters Patent.

Patented Apr. 8, 1919.

Application filed May 25, 1918. Serial No. 236,453.

To all whom it may concern:

Be it known that I, ERNEST OSCAR THALINGER, a citizen of the United States, residing at the city of St. Louis and State of Missouri, have invented a new and useful Game, of which the following is a specification.

This invention relates to improvements in games, and consists in the novel construction hereinafter described.

An object of the invention is to provide a game simulating the game of base ball which may be played upon a table or support for the purpose of amusement, either 15 by juveniles or adults without the exercise of any unusual amount of skill, but which combines a sufficient degree of skill with chance to impart to it a high degree of interest for the players.

With the foregoing general purpose in view, I have designed the construction hereinafter described, reference being made to the accompanying drawing, in which—

Figure 1 is a plan view of the game set 25 up for operation.

Fig. 2 is a plan view of the actuator for batting the ball.

Fig. 3 is a rear elevation of the actuating device.

The game comprises a board designated in such a manner as to constitute a counter to determine the valuation of the play which consists in projecting upon the field a ball by means of a mechanical actuator. The 35 game board is preferably formed so as to constitute a rectangular field 1, the sections of the board being flexibly secured together upon the lines 2 and 3, so that it may be folded into small compass.

One face of the board is ruled to represent a base ball diamond indicated by 4, the home plate being at one edge of the board at a point approximately intermediate the length of the side. The board is 45 also ruled so as to form four valve zones designated on the drawing as "1st base zone", "2nd base zone", "3rd base zone", and "Home zone", and at various positions on the board and placed so as to introduce an element of chance into the game are zones designated on the drawing by the word "Out". The value of each play is determined by the position of the ball after it has been projected from the actuator. Thus, 55 if the ball comes to rest behind the foul line the play counts as a foul strike according

to the usual rules of base ball. If the ball comes to rest within any of the spaces designated "Out", the play is so counted. If, however, it falls within the value zones, 60 a disk or counter is placed upon the base corresponding to the value of the zone in which the ball comes to rest, for instance, if the ball comes to rest within the "1st base zone" a counter is placed upon first base. 65 If the next operation of the actuator causes the ball to fall within the "2nd base zone" the counter on the first base is moved forward to third base and a second counter is placed on second base. If the next operation results in the ball being played in the "3rd base zone" the counters on second and third base are moved to home base, thus scoring two runs. If the next operation results in a home run the counter on third 70 base is moved home and a home run is scored, resulting in four runs.

Each player operates the actuator in succession, continuing the operation until three men strike out as determined by the usual 80 rules of base ball, when the next player operates the actuator continuing the play and determining the inning score by the result of the plays, until such player obtains three men out.

The actuator for projecting the ball comprises a base 5 upon which is removably mounted an upright member 6, preferably formed to represent a base ball player, to carry out the similitude of the game. Attached to the rear face of the member 6 is a standard 7 having a cylindrical extension 8 at its lower end adapted to seat in an opening 9 in the base to support the batter in upright position. Near the upper end 85 of the standard 7 is a channel 10 to receive a bat in the form of a lever 11 which is pivoted on a removable pin 12 extending through an opening in the lever and a cylindrical recess 13 extending inwardly from the top of the standard. The short arm of the lever 11 is rounded at its extremity as indicated at 14 and the long arm of the lever is in the form of a paddle which extends beyond the batter with the wide face extending vertically above the base or support 90 5.

The long arm of the lever is normally actuated forwardly by a U-spring 15 which is fitted in between the member 6 and the 110 inner face of the short arm of the lever.

By contacting a finger of one hand with

the extremity 14 and exerting an inward pressure the operator moves the long arm of the lever to the position indicated in dotted lines in Fig. 2. Upon releasing the pressure the long arm of the lever is snapped forwardly. Within the upper face of the base is a hemispherical recess 16 below which the base is cut out as indicated at 17, so that the lower face of the recess extends into an open space below the base. Immediately below the recess is a spring 18 which is secured at one end at 19 having its free end extending beyond the edge of the base and being slightly up-turned at 20 to form an engaging portion. This spring is depressed by the player with the hand opposite from that utilized in operating the lever, so that when it is released there is an upward movement of the spring which throws the ball 21 placed in the recess 16 upwardly in a vertical direction. The ball is secured to the base by a flexible connection 22. In operating the actuator, by coördinately releasing the lever 11 and the spring 18, the ball is thrown upwardly in the path of lateral movement of the lever 11. The lever has on its front face near the ends thereof and in alinement with the path of the vertical movement initially imparted to the ball by the spring 18, a hemispherical projection 23, so that the ball will be struck by the said projection and be thrown upon the board, the actuator being placed at the side of the board adjacent to home base.

The ball will be projected at various positions upon the board dependent upon the relative contact point between the projection 23 on the lever 11 and the ball at each play, the force of the forward movement of the lever, and upon the recoil imparted to the ball by the flexible connection 22. When the ball has come to rest after each operation the value of the play is determined in the manner above outlined. The game is preferably played in accordance with the established rules of base ball and the highest score for nine innings played determines the winner of the game.

What I claim and desire to secure by Letters Patent, is:

50 1. A game, comprising a ball, an actuator

for the ball, including mechanical means for moving the ball in a vertical direction, mechanical means for projecting the ball laterally from the vertical position, and a board for determining the value of the play according to the point at which the ball comes to rest after having been moved by the actuator. 55

2. A game, comprising a game board for determining the value of the play by the position at which a ball comes to rest after 60 having been projected thereupon, an actuator comprising a base, a spring operated device for moving the ball vertically, and a spring actuated device for striking the ball laterally from the path of movement imparted thereto by the said first-named device whereby the ball is projected upon the board. 65

3. A game apparatus, comprising an actuating device for throwing a ball vertically, a 70 mechanical striker located above the throwing device, said striker having a hemispherical projection thereon so that the ball is projected from the vertical path of movement in various angular directions, and a game 75 board adapted to be positioned so as to receive the ball projected thereon, said game board being marked to determine the value of the play of the ball by the position at which the same comes to rest upon said 80 board.

4. In a game apparatus, the combination of mechanical means for moving a ball in a vertical direction, and mechanical means for projecting the ball out of its vertical path of 85 movement in various angular directions, with a game board for determining the value of play according to the point at which the ball comes to rest after it has been actuated.

5. In a game apparatus, the combination of 90 a ball, a flexible connection for limiting the movement of the ball, mechanical means for moving the ball in a vertical direction, and mechanical means for projecting the ball out of its vertical path of movement in various 95 angular directions, with a game board for determining the value of play according to the point at which the ball comes to rest after it has been actuated.

ERNEST OSCAR THALINGER.
